(57) **CLAIM**

The ornamental design for side mirror shield, as shown and described.

DESCRIPTION

FIG. 1 is an isometric view of a side mirror shield showing my new design;

FIG. 2 is a front elevational view thereof;

FIG. 3 is a rear elevational view thereof;

FIG. 4 is a right elevational view thereof;

FIG. 5 is a left side elevational view thereof;

FIG. 6 is a top plan view thereof;

FIG. 7 is a bottom plan view thereof; and,

FIG. 8 is an isometric operational view of the side mirror shield in a condition of use on the driver side of a semi-truck. In the drawings, the broken lines depict environmental subject matter only and form no part of the claimed design.
